[57] CLAIM

The ornamental design of an upright vacuum cleaner, as shown and described.

DESCRIPTION

FIG. 1 is a perspective view of an upright vacuum cleaner showing my new design;

FIG. 2 is a left side elevational view thereof;

FIG. 3 is a front elevational view thereof;

FIG. 4 is a right side elevational view thereof;

FIG. 5 is a rear elevational view thereof;

FIG. 6 is a top plan view thereof.

The hose shown in broken lines in the drawing figures is shown for illustrative purposes only and forms no part of the claimed design.
